UNITED STATES PATENT OFFICE

129,483

DESIGN FOR A CHEST

Leo Jiranek, Scarsdale, N. Y., assignor to Heywood-Wakefield Company, Gardner Mass., a corporation of Massachusetts

Application March 3, 1941, Serial No. 99,326

Term of patent 7 years

To all whom it may concern:

Be it known that I, Leo Jiranek, a citizen of the United States and a resident of Scarsdale, county of Westchester, and State of New York, have invented a new, original, and ornamental Design for a Chest, of which the following is a specification, reference being had to the accompanying drawing, forming a part thereof, in which Fig. 1 is a perspective view of a chest,

showing my new design. Fig. 2 is a top plan view of the chest. Fig. 3 is a fragmentary vertical sectional view, shown broken away, and on an enlarged scale, through a part of the chest as taken on the line 3—3 of Fig. 2.

I claim:

The ornamental design for a chest, substantially as shown.

LEO JIRANEK.
